Primary Examiner — Mitchell I. Siegel

(57) **CLAIM**

I claim the ornamental design for a golf hole reducer, as shown and described.

DESCRIPTION

FIG. 1 is an exploded top plan view of a golf hole reducer showing my new design;

FIG. 2 is a top plan view of the assembled golf hole reducer;

FIG. 3 is a side elevational view of FIG. 2; and,

FIG. 4 is a bottom plan view of FIG. 2.
